SURFACE ORNAMENTATION OF WALLS.

No. 18,447.

Patented July 10, 1888.

UNITED STATES PATENT OFFICE.

FREDERICK KOSKUL, OF WILLIAMSPORT, PENNSYLVANIA.

DESIGN FOR THE SURFACE ORNAMENTATION OF WALLS.

SPECIFICATION forming part of Design No. 18,447, dated July 10, 1888.

Application filed March 17, 1888. Serial No. 267,578. Term of patent 14 years.

To all whom it may concern:

Be it known that I, FREDERICK KOSKUL, of Williamsport, Lycoming county, Pennsylvania, have invented and produced a new and original Design for the Surface Ornamentation of Walls, &c., of which the following is specification.

The accompanying photograph represents my design.

Said design consists in the parallel bars A, having rounded edges B C D E. Upon each bar appears an elongated elevation, F, having an upper rounded surface. At opposite ends of each bar A appear quadrangular elevations G G', each of which elevations has four

inclined surfaces, H I J K. Upon each elevation G or G' appears another elevation, L, also having four inclined surfaces. Between the bars A and the elevations G appears a curved channel, M, and between the bars A and the elevations G' appears a straight channel, M'.

I claim—

The design for surface ornamentation of walls, &c., substantially as herein shown and described.

FREDERICK KOSKUL.
